UNITED STATES PATENT OFFICE.

LOUIS CHARLES DAUCHER, OF SURESNES, FRANCE.

IGNITION APPARATUS FOR INTERNAL-COMBUSTION ENGINES.

1,160,388.

Specification of Letters Patent. Patented Nov. 16, 1915.

Application filed May 22, 1913. Serial No. 769,234.

To all whom it may concern:

Be it known that I, LOUIS CHARLES DAUCHER, a citizen of the French Republic, and residing at Suresnes, Seine, France, have invented certain new and useful Improvements in Ignition Apparatus for Internal-Combustion Engines, of which the following is a specification.

The subject-matter of my invention is an apparatus for checking the electric ignition of internal combustion engines. While the engine is working the apparatus enables the ignition to be supervised and it indicates whether ignition is normally taking place in all the cylinders. As soon as a defect in the ignition in one cylinder occurs, however, it indicates the same.

The apparatus can be employed in all engines in which a high tension current passes through the spark-plugs.

The apparatus having the form of a small plate is provided with two rows of apertures, of which the one row indicates the weak ignitions in the various cylinders. The second row indicates the faults in the ignition.

The apparatus is connected by a branch conductor with the ignition lead of each spark-plug. It comprises two rows of spark-gaps of various sizes, those of the one row being separated from one another by small air gaps. Those of the second row are separated by larger air spaces and operate only when the ignition at the spark-plugs in question completely fails.

One embodiment of the invention as applied to a four-cylinder internal combustion engine is represented by way of example in the accompanying drawing, wherein:

Figure 1 is a diagram of connections for my apparatus, Fig. 2 is an elevation showing the apparatus on an enlarged scale, and Fig. 3 is a vertical section through the same taken on the line I—I in Fig. 2.

The apparatus is adapted for internal combustion engines having any number of cylinders, in which the electric ignition is effected by a high tension current supplied to the spark-plugs.

In the illustrative embodiment the engine has the four cylinders I, II, III and IV. Ignition in these cylinders is brought about by the spark-plugs B¹, B², B³ and B⁴, to which the high tension current is supplied over a distributor D in the usual manner by the magneto apparatus or the induction

coil. This distributor comprises brushes D¹, D², D³ and D⁴ corresponding in number to the number of plugs and connected with the plugs by the wires F¹, F², F³ and F⁴. 60

According to my invention I branch off from these wires tappings f¹, f², f³, and f⁴ which, together with a common return wire f⁵, are attached to the frame of the engine. These branches f¹, f², f³, and f⁴ lead to the 65 spark-gaps 1, 2, 3 and 4 and 1^a, 2^a, 3^a and 4^a connected together in series in pairs, their middle point or pole 2^b (Fig. 3) being insulated. The action of these spark-gaps 1, 2, 3 and 4 or 1^a, 2^a, 3^a and 4^a is such that small 70 sparks are produced at the spark-gaps 1, 2, 3 and 4 as soon as the corresponding spark-plugs ignite normally, while no sparks pass across the spark-gaps 1^a, 2^a, 3^a and 4^a. As soon as a plug is very dirty and the passage 75 of current is thereby disturbed, sparks are produced at both spark-gaps, while when a short-circuit occurs in the plug no sparks are formed at the spark-gaps used for controlling or supervising the plugs. 80

The spark-gaps are arranged on a plate or slab in various ways. Figs. 2 and 3 show one form in which the plate or slab a consists of insulating material. The plate a has two rows of four holes corresponding 85 to the number of cylinders. In the upper holes c¹, c², c³ and c⁴ are located the spark-gaps 1, 2, 3 and 4, while in the lower holes d¹, d², d³ and d⁴ are the spark-gaps 1^a, 2^a, 3^a and 4^a. The leads f¹, f², f³ and f⁴ are attached to the plate a by nuts n. The current passes from the screws h¹, h², h³ and h⁴ carrying these nuts to the plugs. The screws enable the widths of the spark-gaps 90 to be regulated. For the same purpose the spark-gaps 1^a, 2^a, 3^a and 4^a are provided with screws p¹, p², p³ and p⁴ which are connected by a bar o, from which the return wire f⁵ goes from the screw p⁵ to the engine. The plate a is provided with a back 95 plate s made of insulating material. On the front side of the plate a is a pane of glass r which can be attached together with the back plate s by screws t. The entire apparatus can be mounted at any desired place by the screw u. 100

I claim:

1. The combination with the spark-plugs of an internal combustion engine, of a plurality of pairs of regulatable spark-gaps, each pair of spark-gaps being connected in parallel with one of the spark-plugs and 110

one of the gaps being shorter than the other, the spark-gaps of each pair being connected together in series.

2. The combination with the spark-plugs 5 of an internal combustion engine, of a plate having pairs of holes therein, pairs of regulatable, series-connected spark-gaps at each of said pairs of holes, one of the gaps being shorter than the other, and means connect-

ing each pair of spark-gaps in parallel with 10 one of the spark-plugs.

In testimony whereof, I affix my signature in the presence of two witnesses.

LOUIS CHARLES DAUCHER.
